UNITED STATES PATENT OFFICE.

GEORGE GROOBED, OF CHICAGO, ILLINOIS.

DESIGN FOR A CAR-UNCOUPLING BRACKET.

SPECIFICATION forming part of Design No. 32,641, dated May 8, 1900.

Application filed April 9, 1900. Serial No. 12,023. Term of patent 14 years.

To all whom it may concern:

Be it known that I, GEORGE GROOBED, a citizen of the United States, residing at Chicago, in the county of Cook and State of Illinois, have invented and produced a new and original Design for a Car-Uncoupling Bracket; and I do declare the following to be a full, clear, and exact description of the same, reference being had to the accompanying drawings, forming a part thereof.

Figure 1 is a perspective view of a car-uncoupling bracket, showing the top and one side of my new design. Fig. 2 is a perspective view showing the bottom or reverse side of my design.

As shown by the figures of the drawings, the leading or characteristic features of my design consist of the slotted base A, having the top surface B and bottom surface C in parallel planes, the raised ribs D D projecting from the top surface of the base and lying in planes perpendicular to the plane of the base and oblique to the longitudinal axis of the same, and the raised ribs E E, also projecting from the surface of the base and lying in planes perpendicular to both the said base and the ribs D D, the said ribs D D and ribs E E having slots F F disposed in planes

oblique to the axis of the base and the said ribs E E being provided with perforations G 30 G at right angles to the same.

Lugs H H project from the bottom surface of the base each side of the slot made therethrough, and ribs I and J are disposed at right angles each to the other at the opposite 35 end of the bottom surface of the said base. The sides at K K are parallel with the ribs D D and the end surfaces L L parallel with the ribs E E and the slots F F.

The shapes or configurations of both the 40 leading or characteristic and the subordinate features of the article are clearly disclosed to the eye by the figures of the drawings.

Having described my invention, what I claim as new, and desire to secure by Letters 45 Patent, is—

The design for a car-uncoupling bracket, as herein shown and described.

In testimony whereof I have signed my name to this specification in the presence of 50 two subscribing witnesses.

GEORGE GROOBED.
